United States Patent Office

Des. 209,893
Patented Jan. 9, 1968

209,893

FABRIC FOR GARMENTS

Ann Weiner, Los Angeles, Calif., assignor to Ellson of California, Los Angeles, Calif., a copartnership

Filed May 6, 1966, Ser. No. 2,201

Term of patent 14 years

(Cl. D92—1)

The figure is a plan view of a fabric for garments showing my new design.

I claim:

The ornamental design for a fabric for garments, substantially as shown.
